STRAINER FOR PULP DIGESTERS

Herbert W. Guettler, Glencoe, and Clarence J. Christiansen, Evanston, Ill., assignors to Fibre Making Processes, Inc., Chicago, Ill., a corporation of Illinois

Application February 12, 1936, Serial No. 63,494

11 Claims. (Cl. 92—7)

This invention relates to pulp digesters such as used in the paper making industry, and has to do with the strainer and associated parts of a digester.

It is common practice in operating digesters to circulate the liquor by drawing a part thereof from the digester and returning the liquor thereto, by means of a suitable pump. It is necessary to provide a strainer to prevent withdrawal of the chips and fibres from the digester. The strainer may be located at the top or bottom, or any suitable intermediate position within the digester. This strainer is subjected to high pressures and severe stresses within the digester and must be of adequate mechanical strength and supported in such manner as to eliminate possibility of warping or breaking of the strainer with possible serious results due to the strainer, or parts thereof, becoming detached and dropping into the digester. The strainer must also be of adequate capacity and great care is necessary in connecting this strainer to the conduit for withdrawing the liquor, particularly in digesters employing acid liquor. Such digesters are constructed with an outer shell of ordinary steel, which is readily attacked by the acid, and an inner acid resistant lining. If leakage of acid to the outer shell occurs, with consequent weakening of the latter, serious danger to the operators accrues due to the fact that the digester is operated under relatively high pressure.

In general, our invention is directed to the strainer and associated means such that adequate mechanical strength is provided for, ample capacity of the strainer is assured, and possibility of access of the acid liquor to metal parts readily attacked by the acid is eliminated. Another object of our invention is to provide a strainer and associated supporting means therefore so constructed and arranged that objectionable stresses, due to expansion and contraction of parts, are prevented and ready removal of the contents of the digester, when discharging the same, is not interfered with. A further object is to provide an outlet connection which may be assembled with expedition and facility, and associated means for assuring a seal about certain portions of such connection effective to prevent access of the acid liquor to metal parts susceptible to attack by the acid. Another object is to provide a strainer and associated connection of simple and relatively inexpensive construction and which can be readily replaced and repaired as required. Further objects and ad-

vantages will appear from the detail description.

In the drawings:—

Figure 1 is a transverse sectional view through a digester with a strainer and associated part embodying our invention applied thereto; 5

Figure 2 is a fragmentary vertical sectional view taken substantially on line 2—2 of Figure 1, on an enlarged scale, certain parts being shown in section; 10

Figure 3 is a fragmentary vertical sectional view taken substantially on line 3—3 of Figure 1, on an enlarged scale;

Figure 4 is a fragmentary vertical sectional view taken substantially on line 4—4 of Figure 15 1, on an enlarged scale;

Figure 5 is a fragmentary front view of the central portion of one of the strainer sections, and the associated supporting means therefor, on an enlarged scale relative to Figure 1; 20

Figure 6 is a fragmentary face view of the adjacent end portions of two strainer sections and the supporting means therefor, partly broken away, on an enlarged scale relative to Figure 1;

Figure 7 is a detail perspective view of the 25 means for supporting and closing one end of the strainer;

Figure 8 is a view in elevation, partly broken away and in section, of a pulp digester for using alkali liquor, showing a strainer and associated 30 supporting and connection means embodying our invention applied thereto;

Figure 9 is a sectional view taken substantially on line 9—9 of Figure 8, on an enlarged scale;

Figure 10 is a fragmentary vertical sectional 35 view taken substantially on line 10—10 of Figure 9, on an enlarged scale, broken away and shown in section;

Figure 11 is a fragmentary vertical sectional view taken substantially on line 11—11 of Figure 40 9, on an enlarged scale, partly broken away; and

Figure 12 is a fragmentary vertical sectional view taken substantially on line 12—12 of Figure 45 8, certain parts being shown in elevation and the major portion of the digester being broken away.

In Figures 1 to 7, inclusive, we have shown our invention as applied to a digester used in what is known as the sulphite process, the liquor employed being a solution of sulphurous acid. The digester is, in general, of known construction and comprises an outer shell *a* of ordinary steel and an inner lining *b* resistant to the acid liquor used in the digesting process. A charging neck *c* 55

is provided at the top of the digester and is normally closed by a removable cover *d*, as shown in Figure 8. A discharging neck *e* is provided at the bottom of the digester and has bolted there-to a fitting *f* in the form of an elbow from which extends a discharge pipe *g* controlled by a valve *h*. A pipe *i* extends from elbow *f* for connection to circulating means (not shown) effective for withdrawing liquor from the digester and returning it to the bottom or lower portion thereof. We also preferably provide a pipe *k* to which a portion of the withdrawn liquor is supplied from the circulating means, this pipe being connected to a spray device (not shown) within the digester, adjacent the top thereof, for spraying liquor onto chips which may be exposed above the liquor, thus maintaining the chips moist and preventing objectionable charring thereof. Preferably, we employ a liquor circulating and heating and spraying system which is similar, in general, to that disclosed in United States Patent No. 1,942,685, issued January 9, 1934, to Andreas Christensen, for Sulphite pulp digester system, though our invention is not limited to the use of this particular system and any other suitable or preferred means for circulating the liquor, either with or without associated spraying means, may be employed.

The strainer *15* of our invention comprises a plurality of sections *16* and *16a* disposed in end-wise alignment and opening one into the other. Each of these sections is of arcuate shape in plan and the strainer is disposed in close proximity to the inner face of liner *b*, conforms in curvature to the curvature of the digester and, in the illustrated embodiment, extends the semi-circumference thereof. It will be understood, however, that the extent of the strainer may be varied to suit conditions, and it may extend throughout the entire interior circumference of the digester or for a portion only thereof, whether more or less than half of the interior circumference of the digester, as required.

Each strainer section *16*, as well as section *16a*, is of triangular cross section, comprising an imperforate back wall *17* and perforated upper and lower front walls *18* and *19*, respectively, preferably braced by reinforcing ribs *20* disposed within the strainer section and at the outer faces of these walls. It will be noted that the wall *18* is flat and inclined downward and inward of the digester, wall *19* being flat and inclined downward and outward of the digester. Disposing the walls *18* and *19* in this manner assures that any material which may tend to settle upon wall *18* will be discharged therefrom downwardly into the digester, and that no material can settle upon wall *19*. In this manner we effectively eliminate possibility of material lodging upon the strainer, and thereby assure that the strainer will present no interference to ready discharge of the contents of the digester, which is an important practical consideration.

Each section *16* and *16a* of the strainer is provided, adjacent each end, at its mid-length and intermediate points with reinforcing ribs *21* conforming to walls *18* and *19* and disposed at the inner faces of these walls with respect to the interior of the digester. A mounting strip *22*, formed of metal resistant to the action of the acid liquor, is disposed in contact with back wall *17* of strainer section *16* and in alignment with center rib *21* of each of the sections of the strainer. Strip *22* is provided at each end with an opening which receives the reduced threaded

stud *23* of a bolt *24* extending through lining *b* and provided with a shoulder *25* at the outer end of stud *23*, the latter receiving nut *23a* and washer *23b*. Bolt *24* is provided at its other end with a threaded stud *26* and a shoulder *27* at the inner end of the latter stud. Stud *26* projects through shell *a* of the digester and receives upon its outer end a securing nut *28*, washers *29* of suitable type being confined between this nut and shell *a*. A lead gasket *30* fits about stud *26* and is confined between shoulder *27* and the inner face of shell *a* and provides an effective fluid-tight seal about stud *26*, when bolt *24* is forced toward shell *a* and secured thereto by means of the nut *28* and stud *26*. Spacing washers *31* are disposed about stud *23* for properly spacing strip *22* with reference to the inner face of lining *b*. Clamps *32* are disposed over the studs *23* of bolts *24* and are slotted at *33* for reception of the terminal portions of rib *21*. Fingers *34* of the respective clamps *32*, at each side of the slot *33* thereof, are bent at an angle to the body of the clamp so as to be inclined similarly to walls *18* and *19* of the strainer section *16*. The clamps thus engage about the upper and lower portions of the strainer sections and cooperate with rib *21* to confine this section against lengthwise movement while accommodating transverse expansion and contraction thereof, it being noted that these clamps possess sufficient resiliency for the latter purpose while being maintained in contact with the walls *18* and *19* of the strainer section so as to prevent any objectionable looseness or play of parts. Each strainer section is thus supported at its mid-length in such manner as to accommodate lengthwise expansion and contraction of the section while confining it against lengthwise movement, while also accommodating transverse expansion and contraction of the section, and the bolts *24* serve to support the weight of the strainer section from the steel shell *a* of the digester, to which shell the bolts are directly and tightly secured in the manner above described, thus relieving the lining *b* of any load with respect to the strainer and associated parts.

The ends of the strainer sections are spaced apart a sufficient distance to accommodate lengthwise expansion thereof, as shown at *35* in Figure 6, which is an inner face view of the adjacent end portions of two strainer sections *16* and the mounting means therefor. A bracket *36*, conforming in shape to the adjacent ends of the sections *16*, extends about the ends of these sections between the end ribs *21* thereof. This bracket is suitably secured, by welding or otherwise, to the end of one of the sections, spans the gap *35* between the section ends and extends an appreciable distance along the end of the other section, from which it is free. This bracket thus establishes a telescoping connection between the adjacent ends of the section effective to exclude from the gap therebetween the contents of the digester while accommodating lengthwise expansion and contraction of the sections.

A flat spacing bar *37* is disposed at the ends of these two adjacent sections of the strainer, at the outer face of the back walls thereof, and spans the gap between the ends of these walls. The inner face of spacing bar *37* is recessed at *38*, as shown in Figure 3, to reduce the area of contact between this bar and back walls *17* of the strainer sections for reducing resistance to expansion and contraction of the latter. At each end bar *37* is provided with a boss *39* of rectangular shape. These bosses receive studs *75*

40 extending inwardly from shoulders 41 of bolts 42, which latter project through the lining b. Each bolt 42 is provided with an outer shoulder 43 at the inner end of a screw stud 44 which projects through shell a and receives upon its outer end a nut 45, washers 44a being confined between this nut and the shell. A lead gasket 46 is confined under pressure between shoulder 43 and the inner face of shell a, providing a fluid-tight seal above stud 44. The bolts 42 are thus secured directly to shell a so that the load of the parts carried by these bolts is supported by the shell, relieving the lining b of such load. Reduced screw studs 47 extend inward from studs 15 40 of the bolts 42, and pass through clamps 48, the latter being confined between bosses 39 and nuts 49 screwing onto studs 47. Each clamp 48 is provided with a flange 50 which engages over the associated boss 39 and cooperates therewith 20 to prevent turning movement of the clamp about stud 47. Terminal portion 51 of each clamp 48 is bent at an angle to the body of the clamp and disposed parallel to walls 18a and 19a of bracket 36, the clamp elements 51 contacting these walls 25 adjacent the top and the bottom of bracket 36. In this manner the adjacent ends of the strainer sections are supported for both lengthwise and transverse expansion and contraction and are relieved of stresses incident thereto, entry of chips 30 and fibre between adjacent ends of the sections is prevented, and the load of such sections is supported directly by the outer shell of the digester.

Each end of the strainer structure is closed by a cup-shaped cap member 52 suitably secured 35 thereon, as by welding or otherwise, which cap members may be supported in the same manner as the brackets 36 are supported, so as to accommodate lengthwise and transverse expansion and contraction of the associated strainer sections. 40 Strainer section 16a is similar to the other strainer sections except that it is provided with an outlet member 53 depending from lower wall 19 and defining an outlet opening therethrough, the upper wall 53a of member 53 constituting a 45 continuation of upper wall 18 of sections 16a, these two walls being provided with a common reinforcing rib 21a and member 53 preferably being provided, at its lower end, with a circumferential reinforcing flange 54. Member 53 receives the upper end portion of an elbow 55, conveniently formed of two sections 56 and 57 provided at their adjacent ends with circumferential bolting flanges 58 and 59, respectively, for securing them together. Section 57 of elbow 55 50 is further provided, adjacent its lower end, with a circumferential flange 60 secured by cap screws 61 to flange 62 at the inner end of a sleeve 63. A conduit 64 is bolted or otherwise suitably secured to the outer end of sleeve 63, the latter and the 55 conduit being provided with suitable bolting flanges 65 and 66, respectively. All metal parts with which the acid liquor used in the digester comes into contact, including the strainer, the supporting means therefor, elbow 55, sleeve 63 and conduit 64, are formed of metal resistant to the action of the acid liquor. Conduit 64 serves to conduct the withdrawn liquor to the circulating means previously referred to.

Sleeve 63 is provided, a short distance from its 70 outer end, with a bolting flange 67 of considerably greater width than flange 65. Flange 67 is provided with a thickened annular element 68 of a size to fit snugly within the outer end of a nozzle 69 secured in a suitable manner, preferably by means of rivets 70, to shell a, at the

outer face thereof. Flange 67 of sleeve 63 seats upon the outer face of a flange 71 provided at the outer end of nozzle 69, these two flanges being secured tightly together in a suitable manner, conveniently by bolting. 5

Flange 62, at the inner end of sleeve 63, has an exterior diameter somewhat less than the interior diameter of nozzle 69 so that, in assembling, sleeve 63 may be inserted through nozzle 69 from the outer end thereof and bolted to the nozzle 10 by means of flange 67. Sleeve 63 extends through lining b of the digester, when mounted upon the nozzle 69, and the lining extends about sleeve 63 and between the same and nozzle 69. The latter, like shell a, is of ordinary steel and would 15 be attacked by the acid liquor if the latter were brought into contact with these parts. It is important, for the reasons previously set forth, that this be avoided. No great difficulty is encountered in forming fluid-tight closures about such 20 parts as pass through the lining, where these parts are readily accessible. There may be difficulty, however, in effecting a fluid-tight closure between the lining and the sleeve 63, particularly at the portion of this sleeve which extends within 25 the nozzle 69 and is there not readily accessible. In order to guard against any possibility of leakage of acid liquor about the sleeve 63 into contact with the nozzle 69, we preferably provide means whereby a sealing compound, such as a 30 suitable cement, may be flowed about sleeve 63, into such spaces, if any, as may exist between this sleeve and the portion of the lining extending thereabout. With this object, we provide nozzle 69 with a suitable opening 72 extending 35 radially of the neck of the nozzle. The portion of the lining b extending into nozzle 69, about sleeve 63, may be provided with a passage 73 aligned with opening 72 and extending therefrom to the exterior surface of sleeve 63. This 40 passage may be provided in any suitable manner, and conveniently may be formed by inserting through opening 72, into contact with the exterior surface of sleeve 63, any suitable instrument prior to placing of the portion of the lining which extends into the nozzle. With such instrument in position, when the lining is placed in the nozzle the passage 73 will be formed in the placing of the lining. After the lining has been placed and is in finished condition, a suitable 45 cement may be delivered through opening 72 and passage 73, under appropriate pressure, thus providing a sealing layer 74 extending about sleeve 63 between the lining surrounding this sleeve and, in some instances, between this portion of 50 the lining and flange 68 of sleeve 63. The passage 73 is, of course, filled with and effectively sealed by the compound 74. In this manner possibility of contact of the acid liquor with the nozzle 69 and the shell a, due to leakage about sleeve 63, 55 is effectively eliminated. Preferably the exterior surface of sleeve 63 is roughened at 75, to assure more intimate contact and a correspondingly more effective seal between this surface and the cement or compound 74. Surface 75 of the sleeve 65 may be roughened by grinding, sand blasting, or in any other appropriate manner.

In Figures 8 to 12, inclusive, we have illustrated a strainer and associated parts, embodying our invention, as applied to a digester for use in 70 a well known digesting process employing an alkali liquor. Since this liquor does not attack metal it is not essential that special provision be made to prevent contact between the liquor and the exterior parts of the outlet connection, 75

and the strainer and associated parts may be formed of ordinary steel such as is employed in the shell and nozzle of the digester. The strainer 76 comprises a suitable number of sections 77 disposed with ends in alignment and opening one into the other, this strainer conforming in curvature to the interior of shell *a* and being disposed in close proximity to the inner face thereof, it being noted that the shell has no lining since the alkali liquor does not attack the steel of which this shell is formed. Each of the sections 77 is provided, at its mid-length, with a reinforcing rib 78, which may be formed integral with the upper and lower walls 79 and 80, respectively, of the strainer section, these walls being perforated and connected by an imperforate back wall 81, as before. A spacing bar 82 is securely welded at each end at 83, to shell *a*, and screw studs 84 are welded through the ends of this bar. Slotted clamps 85 are secured upon these studs, between nuts 86 and spacers 87, and receive the end portions of rib 78. In this manner, each section 77 is supported at its mid portion and is confined against lengthwise movement. Since spacing bar 82 is mounted upon shell *a* for expansion and contraction therewith, these parts being of similar metal, transverse expansion and contraction of the strainer section are accommodated.

The ends of adjacent sections 76 of the strainer are spaced apart, as before, and this space is closed by a bracket 88 conforming in shape to the ends of the strainer section and provided with a reinforcing rib 89. This bracket 88 is provided with terminal elements 90 confined between spacers 91 and nuts 92 threaded onto the inner ends of screw studs 93, the latter being welded in the ends of a spacing bar 94 welded at each end, at 95, to the inner face of shell *a*. The bracket 88 fits about the adjacent end portions of adjacent sections of the strainer but is not in tight contact therewith, slight clearance being provided sufficient to avoid interference with free lengthwise expansion and contraction of the strainer sections. The strainer shown in Figure 9 extends more than the semi-circumference of the digester and, as previously noted, may be of any suitable extent up to the full circumference of the digester. The ends of this strainer may be closed in any suitable manner, if it extends less than the full interior circumference of the digester, conveniently by the same means as is provided for closing the ends of the strainer of Figure 1.

One of the strainer sections, designated 77*a*, is provided through the back wall 81*a* thereof with an outlet opening 96. A nozzle 97 is secured to shell *a* by rivets 98, the base flange of this nozzle and the heads of the rivets being welded together and to shell *a*, as shown, to prevent possibility of leakage and assure adequate strength. A sleeve 99 is suitably secured to flange 100, at the outer end of nozzle 97, as by means of cap screws 101 passing through flange 102 of the sleeve. At its outer end sleeve 99 is provided with a flange 103 to which flange 66 of conduit 64 is secured by cap screws 104. Sleeve 99 extends through nozzle 97 and through opening 105 in shell *a*, the inner end portion of this sleeve extending through opening 96 of back wall 81*a* of screen section 77*a*, and being of slightly less exterior diameter than opening 96 to compensate for any slight differences in expansion and contraction of the sleeve 99 and wall 81*a*.

In both forms of our invention illustrated the construction of the strainer is, in general, sub-

stantially the same except as to slight variations, particularly in the supporting means for the strainer, to accommodate the structure to the type of digester with which it is used. In both forms the strainer and associated parts may be assembled and disassembled with expedition and facility, and repair and replacement of parts may be effected with a minimum of delay and labor.

What we claim is:—

1. In combination, a digester, and a substantially horizontal strainer supported within said digester in close proximity to the inner face thereof and conforming in contour thereto, said strainer being of triangular cross-section and having its upper surface flat and inclined downward and inward of said digester, and its lower surface flat and inclined downward and outward of said digester. 10

2. In combination, a digester, and a substantially horizontal strainer of triangular cross-section supported within said digester in close proximity to the inner face thereof and conforming in contour thereto, the upper surface of said strainer being inclined downward and inward of said digester and the lower surface of said strainer being inclined downward and outward of said digester, the outer wall of said strainer being imperforate and at least one of the other walls thereof being perforated. 20

3. In combination, a digester, a strainer therein comprising separate sections disposed in endwise alignment and opening one into the other, means supporting the respective sections at the mid-length thereof while restraining them against lengthwise movement, and means excluding entry of the contents of said digester between adjacent ends of said sections while accommodating independent lengthwise expansion and contraction thereof. 30

4. In combination, a digester, a strainer therein comprising separate sections disposed in endwise alignment and opening one into the other, means supporting the respective sections at the mid-length thereof while restraining them against lengthwise movement, said supporting means accommodating transverse expansion and contraction of said sections, and means excluding entry of the contents of said digester between adjacent ends of said sections while accommodating independent lengthwise and transverse expansion and contraction thereof. 40

5. In combination, a digester comprising a metal outer wall and an acid resistant lining, a strainer therein comprising separate sections disposed in endwise alignment and opening one into the other, means supporting the respective sections at the mid-length thereof while restraining them against lengthwise movement, said supporting means comprising bolts secured to said outer wall and extending through said lining, and means supporting the adjacent ends of said sections and accommodating lengthwise expansion and contraction thereof while excluding entry therebetween of the contents of said digester, said last mentioned means comprising bolts secured to said outer wall and extending through said lining. 55

6. In combination, a digester comprising a metal wall, a strainer therein comprising separate sections disposed in endwise alignment and opening one into the other, each of the sections being provided at its mid-length with abutment elements at its top and bottom, bolts secured to said wall, slotted clamps mounted on the inner ends of said bolts receiving said elements and 70

75

- engaging over the top and bottom portions of the respective sections, brackets engaging about the adjacent ends of said sections and effecting closures therebetween while accommodating lengthwise expansion and contraction thereof, bolts secured to said wall, and clamps mounted on the inner ends of the latter bolts and extending about the top and the bottom portions of the brackets.
- 5 7. In combination, a digester comprising a metal wall, a strainer therein comprising separate sections disposed in endwise alignment and opening one into the other, each of the sections being provided at its mid-length with a transverse reinforcing rib, bolts secured to said wall, slotted clamps mounted on the inner ends of said bolts receiving said rib and engaging over the top and bottom portions of the respective sections, brackets engaging about the adjacent ends 10 of said sections and effecting closures therebetween while accommodating lengthwise expansion and contraction thereof, bolts secured to said wall, and clamps mounted on the inner ends of the latter bolts and extending about the top and 15 the bottom portions of said brackets.
- 10 8. In combination, a digester, a strainer therein comprising a section provided with a depending outlet member, means securing said section to said digester and supporting it therefrom, a nozzle secured to said digester exterior thereof, a sleeve secured to said nozzle and extending therethrough into said digester, and an elbow secured to the inner end of said sleeve and telescoping said outlet member, said elbow being free 20 from said member whereby the latter and said elbow may expand and contract one independently of the other.
- 20 9. In combination, a digester comprising a metal outer wall and a lining therefor, a nozzle secured to the outer face of said outer wall, 25 a strainer within said digester provided with an outlet, a sleeve secured to said nozzle extending therethrough and through said lining and connected to said strainer outlet, said lining extending into said nozzle and about said sleeve, 30 and a sealing compound about said sleeve between the latter and said lining and effective to prevent leakage about said sleeve to said nozzle of the liquid contents of said digester.
- 30 10. In combination, a digester comprising a metal outer wall and a lining therefor, a nozzle secured to the outer face of said outer wall, a strainer within said digester provided with an outlet, a sleeve secured to said nozzle extending therethrough and through said lining and connected to said strainer outlet, the outer surface 35 of said sleeve being roughened, said lining extending into said nozzle and about said sleeve, and a sealing compound about said sleeve between the latter and said lining and effective to prevent leakage about said sleeve to said nozzle of the liquid contents of said digester.
- 35 11. In combination, a digester comprising a metal outer wall and a lining therefor, a nozzle secured to the outer face of said outer wall, a strainer within said digester provided with an outlet, a sleeve secured to said nozzle extending therethrough and through said lining and connected to said strainer outlet, said lining extending into said nozzle and about said sleeve, 40 said nozzle having an opening therein and said lining being provided with a passage from said opening to the exterior of said sleeve, and a sealing compound forced through said opening and passage and between said lining and said sleeve and nozzle and effective to prevent access to the liquid contents of said digester.

HERBERT W. GUETTLER.
CLARENCE J. CHRISTIANSEN. 40
